UNITED STATES PATENT OFFICE.

EDWIN COOPER WILLS, OF NEWARK, NEW JERSEY.

AUTOMATIC OIL-BURNER-CONTROL APPARATUS.

Application filed March 19, 1925. Serial No. 16,782.

My present invention relates generally to fuel oil burners, and more particularly to systems, for instance housing systems, where furnaces are heated by fuel oil burners and it is desired to automatically control such burners so that they will be ignited and operated when the temperature falls below a predetermined point and will be cut off when the temperature rises above another predetermined point, and my object is the provision of an attachment to the ordinary damper controlling system whereby it may be applied to the ignition, operation and control of the burner so that the latter will automatically ignite, operate and cut off under thermostatic influence.

It is a well known fact that various damper control systems are now utilized embodying intermittently actuated motor controlled means including a shaft, the latter connected to the dampers by virtue of slotted crank arms upon the ends of the shaft connected by chains to the dampers to be controlled. In such systems, the control shaft is motor operated and so controlled that upon each motor operation the shaft is turned through 180 degrees or in other words given a half revolution. The actuation of the motor is in turn controlled by thermostatic means so that upon the fall of temperature below a predetermined point the motor will be actuated and the shaft partly rotated and also upon the rise of temperature to a predetermined point the motor will be actuated and the shaft again partly rotated.

When adapting such system to the automatic control of a fuel oil burner utilizing in its employment motor actuated oil and air pumps, the usual crank arms of the intermittently rotating control shaft are removed and I substitute therefore one or more contact wheels controlling independent circuits, one of which is through the pump actuating motor and the other of which is through an ignitor which latter is actuated when the circuit through the motor is initially completed.

The primary object of my invention is to provide simple, inexpensive attachments, readily adaptable to damper controlling devices now in use in order to convert the same for the control of a fuel oil burner and a further object is the provision of means of this nature which will be positive and effective in action as well as inexpensive both in first cost and in use.

In the accompanying drawings, which illustrate my present invention and form a part of this specification:—

Figure 1 is a perspective view more or less diagrammatic showing the complete system with the exception of the thermostat;

Figure 2 is a side view of the motor actuated control unit shown in Figure 1;

Figure 3 is a similar view illustrating a slightly modified form of the attachment as applied to the motor control unit;

Figure 4 is a detail perspective view of certain of the parts of the motor control unit with my invention applied thereto, and

Figure 5 is a diagram of the entire system.

Referring now to these figures and particularly to Figures 1 to 5, inclusive, I have shown in Figure 1 a furnace 10 into which a fuel oil burner indicated generally at 11 is extended. This burner may be of the type as shown for instance in my Patents Numbers 1,493,584 and 1,510,639, respectively dated May 14, 1924, and October 8th, 1924, and may as shown be provided within the furnace with a silencer as for instance shown in my application Serial Number 3,116, which was filed in the United States Patent Office January 17th, 1925.

Adjacent to the lower discharge end of the silencer, the latter of which is indicated at 12 in Figure 2, there is supported in any suitable manner a spark plug 13 whose purpose is to ignite the mixed oil and air where it is emitted from the lower larger end of the silencer, the spark plug being included in a circuit including wires 14 and 15.

To the burner 11 oil and air supply pipes 16 and 17, respectively, lead from oil and air pumps 18 and 19, the former of which has an oil supply pipe 20 which may extend from any suitable source of oil supply as for instance a buried tank such as commonly employed for this purpose.

The oil and air pumps 18 and 19 are simultaneously actuated by a motor 21 and the actuating circuit of this motor includes wires 22 and 23.

In carrying out my invention I may, as shown, employ the well known system of the Minneapolis Heat Regulator Co. ordinarily used for the purpose of mechanically controlling the furnace dampers, and I have shown certain parts of this system in Figure 5 including the thermostat, generally indicated at 24, from which wires 25, 26 and 27 lead down to the binding posts 28, 29 and 30

of a control unit or box 31 having mounted therethrough the usual control shaft 32 and having therein a shaft actuating motor 33 shown in Figure 4 as well as certain other parts to be presently described and also having as usual a transformer (not shown) to which the main line or 110 volt leads 34 and 35 are connected. The line voltage is reduced in the transformer in practice to approximately 8 volts which I tapped off to the motor, and through the latter to the binding posts 28, 29 and 30, and wires 14 and 15 forming the spark plug circuit may be taken from the wires 25 and 27 as clearly shown in both Figures 1 and 5 assuming it is desired to use but 8 volts at the spark plug. On the other hand the wires 22 and 23 forming the motor actuating circuit may be taken from the line or in other words from the main line leads 34 and 35 as also shown in Figures 1 and 5.

As indicated in Figure 4, the motor 33 within the control unit or box 31 is in the "Minneapolis" system above referred to 25 geared through reducing gears 36 to the control shaft 32 and the latter is controlled in its rotation to a half revolution each time the motor circuit is completed at the thermostat 24, by virtue of means including a 30 notched disk 37 on the shaft 32 with which a latch member 38 coacts, the disk 37 having its notches diametrically opposed and the latch member 36 being in practice electromagnetically controlled in such manner that 35 at each actuation it is raised and then immediately lowered for engagement with the next or diametrically opposite notch of the shaft during the rotation of the latter.

As before stated, in the ordinary use of the 40 control unit or box 31 in the "Minneapolis" system for the mechanical control of furnace dampers the control shaft 32 has upon its opposite ends slotted crank arms (not shown) but in the present instance in order 45 to adapt the same to the attachments proposed by my invention, these crank arms are removed and in their place my invention proposes contact wheels 39 and 40 according to Figures 1, 2, 4 and 5, the latter of which 50 cooperate with the spaced contacts 41 and 42, the contacts 41 engaging the periphery of wheel 39 at spaced points and the contacts 42 similarly engaging the periphery of wheel 40 at spaced points. The contacts 41 are 55 furthermore connected within the wire 15 of the spark control circuit while the contacts 42 are connected within the wire 22 of the motor circuit, the spaces between these contacts 41 and between the contacts 42 normally constituting gaps in the circuits so that 60 the latter are only complete when the wheels 39 and 40 are turned to such position that their peripheral contact plates 43 and 44, respectively, bridge the spaced contacts 41 and 42.

As between the two contact wheels 39 and 40, the peripheral contact strip 44 of wheel 40 is somewhat longer than the contact strip 43 of wheel 39 so that the circuit of motor 21 will be completed slightly in advance of the 70 completion of the circuit through the spark plug 13 and will remain closed when the control shaft 32 has come to rest and when the contact strip 43 has at that time completely passed the contact members 41 or at least 75 passed one of them.

In its action the shaft 32 rotates in the direction of the arrow in Figure 4 and consequently the contact wheels 39 and 40 also rotate in the direction of the arrows thereon, 80 the position of the parts shown in Figure 4 being that occupied by these parts after operative movement of the shaft 32 to turn on the burner occasioned by a fall of temperature below the set temperature of the thermostat which has completed a circuit through the motor sufficient to rotate shaft 32 through a half revolution. During this movement the contact strips 43 and 44 have bridged the contact members 41 and 42 90 whereupon motor 21 has been placed in operation to bring about pumping of oil and air to the burner 11 and a circuit has been developed at the spark plug 13 resulting in ignition of the burner. It will be noted that 95 except for the contact plates 43 and 44 the peripheries of the contact wheels 39 and 40 are covered with non-conducting material at 45 and that while the circuit through the pump actuating motor 21 remains closed with the parts in the position shown in Figures 1 and 4, the circuit through the spark plug 13 has been broken by virtue of the 100 passage of the contact plate 43 past the contact members 41.

As shown in Figure 1, the contact members 41 and 42 are preferably in the nature of spring actuated carbons in carbon holders, the latter disposed upon brackets 46 adjustably mounted upon the ends of a supporting bar 47 which is extended across and secured to the lower portion of the control unit or box 31.

With the parts in the position shown in Figure 4 the burner is in operation and the heat commences to rise and as soon as it reaches the set temperature of the thermostat, the circuit through motor 33 is again completed and the control shaft 32 is revolved through 180 degrees, whereupon the contact wheels 39 and 40 are similarly rotated so that the contact plates 43 and 44 are shifted to positions diametrically opposite to the positions shown in Figure 4. Thus the contact plates 43 and 44 are both free of 115 the contact members 41 and 42 and the circuit through the pump actuating motor 21 is thus broken as well as the circuit through the spark plug 13.

As shown in Figure 3 my improvements 120

are capable of modification to the extent of using but a single contact wheel 48 upon one end of the control shaft 49, the stationary contacts 41^a and 42^a being mounted adjacent to one another and controlled by a single elongated contact plate 50 upon the non-conducting peripheral strip 51 of the wheel. The wheel 48 in this modified form of the invention is so adjusted that in its operative movement to turn on the burner, strip 50 moves across the contact members 41^a and 42^a and comes to rest after its trailing end has passed the contact members 41^a or at least one of them, whereby the circuit 15 through the spark plug is completed and then broken and the circuit through the pump controlling motor is made and maintained until the next effective movement of the control shaft.

20 I claim:—

1. In a burner control apparatus including oil and air pumps, a motor for actuating said pumps and a spark plug for igniting a burner, the combination with a thermostatically controlled unit having a controlling shaft intermittently movable in half turns, of means forming independent circuits through the said actuating motor and the said spark plug and each including spaced contact members, and means rotating with the said control shaft for bridging the said contacts.

2. In a burner control apparatus including oil and air pumps, a motor for actuating said pumps and a spark plug for igniting a burner, the combination with a thermostatically controlled unit having a controlling shaft intermittently movable in half turns, of means forming independent circuits through the said actuating motor and the said spark plug and each including spaced contact members, and means rotating with the said control shaft and arranged to bridge and pass the contact members of the 35 spark plug and to bridge and remain in lapping relation over the contacts of the motor circuit, whereby the motor will be continued in operation after action of the spark plug has been completed.

3. In a burner control apparatus including oil and air pumps, a motor for actuating said pumps and a spark plug for igniting a burner, the combination with a thermostatically controlled unit having a controlling shaft intermittently movable in half turns, of means forming independent circuits 40 through the said actuating motor and the

said spark plug and each including spaced contact members adjacent opposite ends of said control shaft, and contact wheels secured upon said shaft ends having non-conducting peripheries in engagement with said contact members, and contact strips on said peripheries to bridge the said contact members.

4. In a burner control apparatus including oil and air pumps, a motor for actuating said pumps and a spark plug for igniting a burner, the combination with a thermostatically controlled unit having a controlling shaft intermittently movable in half turns, of means forming independent circuits through the said actuating motor and the said spark plug and each including spaced contact members adjacent opposite ends of said control shaft, and contact wheels secured upon said shaft ends having non-conducting peripheries in engagement with said contact members, and contact strips on said peripheries to bridge the said contact members, the contact strip controlling the motor circuit being of substantially greater length than the contact strip controlling the spark plug circuit.

5. In combination with a control box, a control shaft therein, and thermostatically controlled means for intermittently moving said shaft in half revolutions, of a supporting bar attached to the box, brackets on said bar, a pair of spaced contact members carried by each bracket, and contact wheels on the shaft ends, each wheel having a non-conducting peripheral portion in engagement with a pair of said contact members and having a contact plate thereon adapted 90 to bridge the contact members in one position.

6. In combination with a control box, a control shaft therein, and thermostatically controlled means for intermittently moving 100 said shaft in half revolutions, of a supporting bar attached to the box, brackets on said bar, a pair of spaced contact members carried by each bracket, and contact wheels on the shaft ends, each wheel having a non-conducting peripheral portion in engagement with a pair of said contact members and having a contact plate thereon adapted 105 to bridge the contact members in one position, the contact plate of one wheel being of 110 substantially greater length than the contact plate of the other wheel.
